(57) **CLAIM**

The ornamental design for automotive diagnostic scan tool, as shown and described.

DESCRIPTION

FIG. 1 is a front upper perspective view the automotive diagnostic scan tool showing my new design;

FIG. 2 is a top plan view thereof;

FIG. 3 is a side elevational view thereof;

FIG. 4 is a front elevational view thereof;

FIG. 5 is an opposite side elevational view thereof;

FIG. 6 is a rear elevational view thereof; and,

FIG. 7 is a bottom plan view thereof.

The broken lines, and unshaded surfaces bound on all sides by broken lines, represent portions of the article that form no part of the claimed design.

1 Claim, 3 Drawing Sheets(56)
